United States Patent Office

Des. 174,476
Patented Apr. 12, 1955

174,476

SHOE

Leonard L. Taicher, Miami Beach, Fla., assignor to Pan American Modes, Inc., Miami Beach, Fla., a corporation of Florida

Application October 25, 1954, Serial No. 32,809

Term of patent 14 years

(Cl. D7—7)

Fig. 1.

Fig. 2.

To all whom it may concern:

Be it known that I, Leonard L. Taicher, a citizen of the United States, residing at Miami Beach, county of Dade, State of Florida, have invented a new, original, and ornamental Design for a Shoe, of which the following is a specification, reference being had to the accompanying drawing, forming a part hereof.

Fig. 2 is a side view thereof; and

Fig. 3 is a plan view thereof.

I claim:

The ornamental design for a shoe, as shown.
